INSULATED ELECTRICAL TERMINAL

John E. Johanson, Boonton, N. J., assignor to
 Aircraft Radio Corporation, Boonton, N. J., a
 corporation of New Jersey

Application February 21, 1938, Serial No. 191,813

2 Claims. (Cl. 174—60)

This invention relates to insulated electrical terminals and particularly to insulated electrical terminals for use in radio transmitters and receivers.

5 It is frequently desirable to enclose various electrical units in tightly sealed metal cans to protect the units from the moisture of the air, and the methods previously employed have not been entirely satisfactory in the case of small units, 10 such as by-pass condensers, that are to be used at high frequencies.

Objects of this invention are to provide insulated electrical terminals, having good electrical characteristics when used at radio frequencies.

15 Objects are to provide insulated terminals in which the terminal or terminal members extend through and are carried by a disk of insulating material, the disk being secured within a ring having a flange that is riveted, soldered or otherwise attached to the housing or panel of the radio device. More specifically, objects are to provide hermetically sealed housings for electrical units, the units having electrical terminals that extend through the housing and are insulated therefrom. Objects are to provide sealed electrical 25 units of the type stated in which the insulated terminals are tubular members through which the leads of the unit extend, the tubular members being deformed mechanically to seal their bores 30 and then soldered to the leads at and across their outer ends to insure good electrical contacts and a tight sealing of the housing.

These and other objects and advantages of the invention will be apparent from the following 35 specification when taken with the accompanying drawing in which:

Fig. 1 is an enlarged central section through a tubular terminal member;

Fig. 2 is an enlarged central section through 40 an insulated terminal assembly embodying the invention, the assembly being shown in position for mounting on a panel or casing;

Figs. 3 to 5, inclusive, are central sections 45 illustrating successive steps in the connection of a lead to the terminal assembly;

Fig. 6 is a central section through a modified form of a hollow terminal member;

Fig. 7 is a similar section showing the terminal member mechanically sealed upon a lead;

Fig. 8 is an enlarged side elevation, with parts 50 in section, of a shielded condenser assembly, the terminals being of the type shown in Figs. 6 and 7;

Fig. 9 is a plan view of the same;

Fig. 10 is a side elevation, partly in section, of

an insulated terminal assembly of the plug type; and

Fig. 11 is a fragmentary perspective view of an insulated terminal construction for small resistor units.

In the drawing, the reference numeral 1 identifies the outer stem of a tubular terminal member having an enlarged base section 2 and a relatively thin-walled inner sleeve 3. The inner angular face 2a of the base is undercut or "raked" 10 at a small angle to insure a clamping action at the periphery of the base section when the sleeve 3 is passed through an opening in an insulating disk 4 and spun or expanded upon a washer 5 to secure the terminal member to the disk. 15

The insulating disk 4 is preferably an assembly of punched sheets of mica when the terminal is to be used on parts of radio equipment and/or when the terminal assembly is to be air tight. The outer edge of the insulating disk 4 is seated 20 on an internal shoulder of a mounting sleeve 6 and is secured therein by spinning the larger diameter end 6a of the sleeve down upon the metal washer 7 that rests upon the disk 4. The smaller diameter end 6b of the sleeve is to be 25 spun outwardly, as shown in dotted lines in Fig. 2, to secure the mounting sleeve and terminal assembly to the panel or casing 8.

The insulated terminal construction of Fig. 2 is particularly adapted for use with electrical 30 units that are hermetically sealed in metal casings. Mica is brittle but is protected against damage during the spinning operation by the metal washer 7, and the coefficient of expansion 35 of mica is such that the tight connections to the metal parts are not loosened by temperature changes. The assembly, when completed to the extent shown in solid lines in Fig. 2, may be impregnated with wax to preclude any leakage of air through the mica disk 4 when the terminal 40 is to be used on a sealed container.

The successive steps in the connection of a lead to the insulated terminal stem 1 are shown in Figs. 3 to 5. The lead 9 is passed through the bore of the terminal member, and the stem 1 is then crimped or rolled to force a section 1a into tight engagement with the lead 9, Fig. 4. The end of the lead 9 is cut off and solder 10 is applied to the outer ends of the stem 1 and lead 9 to make a good electrical connection and to form a further seal for the bore of the terminal. 45

As shown in Figs. 6 and 7, the outer end 1b of the terminal member 1' may be enlarged 50 to provide ample metal for the mechanical seal 55

and a flat surface of appreciable size to receive solder 10'.

An application of the invention to a sealed condenser assembly is shown in Figs. 8 and 9. The 5 mounting rings 6 of the several terminals are riveted into openings in the upper wall of the shield can 11, and solder 12 is applied at the edges of the rings 6 to form tight joints with the shield can. The condensers 13 are placed in the can in 10 the usual manner, and the condenser leads are passed through the bores of the terminal members. Wax may be filled into the can 11 before the bottom 14 is soldered to the can.

The terminals are next mechanically sealed 15 upon and then soldered to the respective leads 9. The electrical unit or condenser block can be connected into a radio circuit in the usual manner. The casing has integral lugs 15 for securing the unit to a chassis, and the leads 16 to the external circuit are twisted upon and soldered to the terminal stems. It is particularly to be noted that the soldering operations do not present any difficulties as the bores of the terminal members are sealed mechanically upon the leads 9. The 20 pressure within the sealed can will differ materially from atmospheric during the soldering operations but the mechanical seal prevents the molten solder from flowing into the casing in the case of a reduced pressure within the casing.

Other types of terminal members may be secured 25 to the insulating disk when pin or socket connections are desired. The assembly illustrated in Fig. 10 includes a plurality of flexible pin terminals 17 whose lower ends pass through mica disk 18 and are riveted over upon the soldering lugs 19. The mica sheets of the disk 18 are secured in a ring 6' by spinning the end of the ring sleeve down upon the metal washer 7' which protects the mica during the spinning operation. 30

40 The assembly is secured within an opening in a panel 8' in the manner described above with reference to Fig. 2.

The form of the invention shown in Fig. 11 provides a compact terminal block assembly for 45 connecting a number of small resistor units into a radio circuit. Terminal assemblies such as shown in Fig. 2, but with soldering lugs 5' in place of the washers 5 of Fig. 2, are mounted in pairs on a sheet 20 of mica or other insulating material, the spacing of the terminals of each

pair being somewhat greater than the length of the resistor units 21. The "pig-tail" leads 22 of the resistors are bent over at right angles, inserted in the bores of the terminal stems 1, and secured by applying solder 23. Circuit connections to the resistors are made at the soldering lugs 5', and the resistor assembly may be supported mechanically by those connections or, preferably, by bolting the insulating strip 20 to the chassis of the radio apparatus. 5

The embodiments herein described are typical of the invention and it is to be understood that other variations which may occur to those skilled in the art fall within the spirit of my invention 10 as set forth in the following claims. 15

I claim:

1. In a hermetically sealed assembly of the type including an electrical unit within a closed metal casing, a tubular metal terminal having an inner end opening into the closed metal casing, means sealing the inner end of the tubular member to and insulating the same from the casing and a lead for the electrical unit extending through said tubular member; the combination with said tubular member of means blocking the flow of air to and from the casing through said tubular member, said blocking means comprising metal of the tubular member deformed mechanically into sealing engagement with said lead and solder uniting the lead and tubular member at a point more distant from the casing than the deformed metal of the tubular member. 20

2. In a hermetically sealed assembly of the type including an electrical unit within a closed metal casing, a tubular metal terminal having an inner end opening into the closed metal casing, means sealing the inner end of the tubular member to and insulating the same from the casing and a lead for the electrical unit extending through said tubular member; the combination with said tubular member of means blocking the flow of air to and from the casing through said tubular member, said blocking means comprising solder uniting the outer ends of the tubular member and the lead and metal of an intermediate portion of the tubular member mechanically deformed into sealing engagement with said lead. 35
